Primary Examiner — Shawn T Gingrich*Assistant Examiner* — JennyLou M Binas(74) *Attorney, Agent, or Firm* — Eric Karich; Karich & Associates(57) **CLAIM**

The ornamental design for a dryer ball as shown and described.

DESCRIPTION

FIG. 1 is a perspective view of a dryer ball, showing the new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

The broken lines shown in the figures are for the purpose of illustrating a portion of the dryer ball and form no part of the claimed design.
